UNITED STATES PATENT OFFICE

CHARLES HEDBERG, OF CHICAGO, ILLINOIS

SNOW AND ICE REMOVER

Application filed July 6, 1931. Serial No. 548,835.

My invention relates to a device especially intended for removing snow and ice from sidewalks and the like; the invention having for its object the provision of a device which may be manually operated and which involves removable means to adapt the device for the removal of loose or unpacked snow, while, on the other hand, permitting said means to be quickly applied or attached to the main body portion when required; said means being constructed to provide a plurality of cutting surfaces formed to cut into and beneath the packed snow and ice.

One object of the invention is the provision of a device of this character which will be inexpensive in manufacture, while at the same time possessing the necessary strength.

The objects and advantages of my invention, as well as the advantages inherent in the invention, will all be readily comprehended from the following detailed description of the accompanying drawing wherein:

Figure 1 is a perspective view of my improved device, with a portion of the handle broken away.

Figure 2 is a top plan view with portions of the handle broken away.

Figure 3 is a perspective view of the main body portion of the device, illustrating the initial bending; the diagonal dotted lines showing where it is to be bent backward so as to dispose the side portions in the opposite direction.

Figure 4 is a perspective view of said main portion, viewed from the rear side.

Figure 5 is a front view of the intermediate portion of the auxiliary member, illustrating the manner of forming the cutting teeth; certain of the teeth being shown before bending, while others are bent into final position.

The specific embodiment of my invention, as illustrated in the drawing, comprises a main body portion 10, which preferably consists of a comparatively thin sheet of metal, namely a thin gauge and preferably rectangular steel plate of desired length. The plate 10 is then bent at its transverse center indicated at 11 and the sheet on opposite sides of the vertical axis or line 11 is then bent in

the opposite direction along the diagonal or upwardly diverging lines indicated at 12—12 to permit the portions intermediate of the central line 11 and the two diverging lines 12, 12 to fold into parallel relation and thus provide the two side shoe portions or wings 13, 13 which slope rearwardly on opposite sides of the vertical median line at any desired angle.

Creasing or bending the plate in the manner described provides the device with the required slope rearwardly toward the top longitudinal edge and the forward side with a forwardly presented shearing nose or wedge at 14 and positions the lower longitudinal edges 15 of each wing or side section 13, 13, in the same horizontal plane.

In order that the entire lower longitudinal edge of the body portion may be in the same horizontal plane, the lower edge of the plate intermediate of the central crease or fold 11 and the two diagonal folds 12, 12 is cut away in the inverted V-shape manner indicated at 16 in Figures 3 and 4.

It is apparent that by folding the sheet back upon itself intermediate of the folds or bends 11 and 12, 12 provides the body portion with the rearwardly extending flange portion 17 to which the lower end of a suitable handle 18 is preferably removably secured, as for example by the bolts indicated at 19; the handle 18 being shown as preferably slotted at its lower end to receive the attaching flange portion 17 therein, thus permitting the bolts 19 to firmly clamp the handle to the shoe or main body portion 10 and at the desired upwardly rearward inclination.

The handle 18 is also braced and rigidly held in place by the downwardly and rearwardly sloping brace 20. The brace 20 is shown in the form of a flat metal bar bent around the handle 18 as indicated at 21; the handle encircling portion 21 being firmly clamped about the handle 18 by bolt and nut, as indicated at 22.

The brace bar 20 has its ends bent into the diverging manner shown in Figures 1 and 2 and the ends in turn riveted or otherwise suitably secured to the transversely disposed wing

brace bar or member 23, which may be in the form of an angle bar or of any desired construction, with the ends of the bar 23 welded, riveted, or otherwise suitably secured to the 5 respective wing portions 13, 13.

5 The wings 13, 13 are thus not only firmly supported at their rear ends to withstand rearward flexing pressure, but the handle 18 is also firmly held in place.

10 The device, as thus described, constitutes a complete snow remover adapted for use in removing loose or unpacked snow; the upwardly and rearwardly sloping sides affording less resistance and causing the snow to be 15 thrown toward opposite sides of the device.

When the snow has become more or less packed, due to travel thereover, or ice has been formed therebeneath, the lower straight edges of the wing portions 13, 13 of the body would 20 be apt to slide over the packed or trodden portions of the snow by reason of the resistance offered by the packed snow or ice.

In order to adapt the device to conditions 25 of this sort and to provide a device which will entirely remove the packed as well as the loose snow and ice, I provide an auxiliary member or shoe 24 which consists of a rectangular sheet metal plate bent centrally transversely to conform to the main body portion 10, see 30 Figure 5.

The lower longitudinal edge of the shoe 24 is bent outwardly horizontally and this horizontal portion is then slit or cut at predetermined distance apart transversely of the 35 horizontal portion to provide a plurality of partially severed portions or teeth 25. The various portions 25 are then folded or bent upwardly along a line extending from the outer end of a forward slit (relative to the forward 40 nose of the device) to the inner end of the next adjacent slit thus providing each tooth or partially severed portion with the upwardly disposed somewhat triangular portion 26. It is apparent from the construction shown and 45 described that each tooth 25 is thus provided with two cutting edges, namely a lower horizontally cutting edge at 27, disposed at an angle to the line of travel, and the upwardly and rearwardly sloping cutting edge at the 50 forward edge of the triangular or diagonally bent portion 26, which edge will be disposed in a direction generally parallel with the forward nose of the device.

55 With my improved cutting shoe attached to the device, it is apparent that the forward horizontal edge of each tooth 25 will ride along the pavement and the packed snow or ice will be cut into small particles by the 60 forward edges of the upwardly bent diagonal portions 26 of the teeth.

The plurality of small teeth cause the hard packed snow and ice to be quickly severed or broken into small particles without requiring 65 undue power on the part of the user of the

device, as the horizontal forward edge of each tooth will cut beneath the packed snow and ice while the sloping cutting edges will sever the same into small portions which will be thrown toward opposite sides of the device by 70 the vertically sloping main part of the shoe.

The shoe 24 is preferably removably secured to the main body 10 by suitable bolts as at 28, and with the lower toothed portion 75 preferably arranged beneath the plane of the lower edge of the body portion, as shown in Figures 1 and 2.

I have shown and described this shoe 24 consisting of a single sheet metal plate, although it may be composed of separate sections or plates, and the preferred exemplification of the invention has been described in terms employed merely for purposes of description, as modifications may be made without, however, departing from the spirit of my 80 invention.

What I claim is:

1. In a device of the character described, a body portion composed of a single piece of sheet metal bent transversely at its vertical 90 center line and diagonally on opposite sides of said first bend, the diagonal bends converging at bottom toward said first bend to provide a rearwardly disposed flange portion, the body portion on opposite sides of the 95 diagonal bends being disposed rearwardly from and at an angle to said flange portion, said body portion inclining rearwardly toward the upper longitudinal edge thereof; a handle secured to said flange portion; a horizontally arranged brace member intermediate of the rear ends of the body portion; and a brace member intermediate of the handle and said first mentioned brace member.

2. In a device of the character described, a body portion composed of a single sheet of metal bent transversely intermediate of its ends to provide a rearwardly disposed flange portion and the portions on opposite sides of the flange bent rearwardly into 100 wedge-shape and inclining rearwardly toward the top of the body portion; and a handle secured to said flange portion.

3. In a device of the character described, a body portion composed of a single piece of sheet metal bent intermediate of its ends to provide a rearwardly disposed triangular shaped flange, the lower edge of said sheet intermediate of said bends having an inverted 115 V-shape cut-out portion so as to have the lower edge of the sheet on opposite sides of said flange arranged in the same horizontal plane, said body on opposite sides of the flange diverging rearwardly and the forward face inclining rearwardly toward the top; and a handle formed to receive said flange portion and secured thereto.

4. A device of the character described comprising a body portion composed of a single 130

piece of sheet metal bent into wedge-shape with its intermediate portion bent back upon itself into a triangular shaped flange to provide a handle attaching portion; a handle secured to the rear side of the body portion and to said triangular flange; and a cutting shoe composed of sheet metal bent into V-shape to conform to said body portion, the lower edge of the shoe being provided with 5 a plurality of teeth formed with forwardly sloping horizontal cutting edges and with upwardly and rearwardly sloping cutting edges.

5. In a snow and ice remover, a cutting shoe 15 composed of a single piece of sheet metal bent into V-shape, the lower longitudinal edge of the shoe being disposed horizontally outward and slit transversely to provide a plurality of partially severed rectangular 20 portions, each portion being bent upwardly along a line extending from the forward outward corner to the rear inward corner of 25 each portion so as to provide a plurality of forwardly sloping horizontally disposed cutting edges and a plurality of upwardly disposed rearwardly sloping cutting edges.

CHARLES HEDBERG.
